UNITED STATES PATENT OFFICE.

EDWARD A. FITZGERALD, OF HIGHWOOD, ILLINOIS.

ELECTRICAL SIGNALING DEVICE.

1,014,588.

Specification of Letters Patent.

Patented Jan. 9, 1912.

Application filed December 9, 1909. Serial No. 532,215.

To all whom it may concern:

Be it known that I, EDWARD A. FITZGERALD, a citizen of the United States, and residing at Highwood, in the county of Lake, State of Illinois, have invented a new and useful Improvement in Electrical Signaling Devices, of which the following is a complete specification.

The main objects of this invention are to provide an electrical signal adapted to be operated from a high voltage circuit, and to produce either an audible or a visible signal; to provide an electrical signal of very cheap and simple construction, and which is both durable and effective in its operation and not liable to get out of repair; to provide an electrical signaling device especially adapted for railway crossings, but which may be used for many other purposes; and to provide an electrical signaling device adapted to be used upon either double or single track systems.

A specific construction embodying the invention is illustrated in the accompanying drawings, in which:

25. Figure 1 is a plan view of the switch, and showing the track broken; Fig. 2 is a fragmentary, sectional view of the track with the switch in side elevation. Fig. 3 is a fragmentary, sectional view of the track 30 with the release in side elevation. Fig. 4 is a plan view of the release and showing the track broken. Fig. 5 is an enlarged detail of the magnets. Fig. 6 is a diagrammatic plan view of the wiring for the signal.

In the construction shown the device is shown as a railway crossing signal for a double track railway system. On either side of the crossing 1, a few of the ties 2 are cut 40 away beneath one rail 3 of each track, to provide a space 4 beneath the rails, as shown more clearly in Figs. 2 and 3, to permit the rail to be bent downwardly by the weight of a passing train. On the side of the crossing 45 from which the train approaches is the switch mechanism 5, and on the side from which the train leaves is the release mechanism 6.

The switch is constructed in the following 50 manner: A bar 7 of spring steel is bent to a U shaped form, having a long upper arm 8 and a short lower arm 9. The arm 9 is rigidly bolted to the tie 2, at a distance from the rail, and the upper arm 8 projects 55 beneath the rail head into position to be depressed by the rail when a train is passing

over the track. Beneath the upper arm 8 are two electromagnets 10 and 11, which are carried in a case 12 and are mounted on a base 13 of slate or other preferred insulating material carried on the tie 2. The magnetic circuits are independent of each other, and the magnets are so wired that their two circuits are parallel and are connected in the core 14 of the magnet 10.

Rigidly secured on the tie between the magnets and the rail are the metal posts 15 on which is fulcrumed the flexible lever 16 of copper. One end of the lever projects over the magnets and is provided with an iron armature 17 adapted to be attracted by and to engage the end of the core 14 when said end of the lever is down. Carried on the magnet 10 in electrical connection with the core 14 is a carbon contact piece 18, and carried on the end of the lever 16, above said contact 18, is a carbon contact piece 19, which is connected with the lever by means of a leaf spring 20 of copper, so that when brought into engagement with the contact piece 18, it will strike with a sliding motion and keep the contacts clean. On the other end of the lever 16 is an adjustable counterweight 21 adapted to normally hold the armature 17 and contact 19 out of engagement 85 with the core 14 and the contact 18, respectively. On the under side of the arm 8 of the bar 7 is a block 22 of iron adapted to limit the upward movement of the lever and to force the lever downwardly to bring the 90 contacts into engagement when the end 8 is depressed by the movement of the rail. Ground wires 23 connect the posts 15 with the rail and act to connect the current from the lever 16 with the earth.

The release is constructed as follows: A spring bar 24, similar to the bar 7, is secured to a tie 2 on the opposite side of the crossing from the switch, and has its upper arm projecting beneath the rail head. An insulator 25 is secured on the tie beneath the upper arm of the bar 24, and a copper contact 26 is carried on said insulator and projects beyond the insulator toward the rail. On the projecting end of the contact 26 is 105 a plurality of fingers 27 of phosphor bronze, adapted to contact with platinum points 28 on a movable copper contact 29, which is secured to an insulator 30 on the under side of the upper arm of the bar 24. A binding post 31 is carried on the contact 29, and a binding post 32 is carried on the insulator

25. A wire 33 connects the binding posts 31 and 32 and is supported on insulators 34, which are carried on the bar 24. A trolley tap 35 leads from the trolley and is provided 5 with a fuse box 36, and connects with an electric bell 37. Leading from the bell are wires 38 and 39 which provide parallel circuits leading to the tracks. In each wire are a plurality of lamps 40 or other resistance adapted to reduce the current to the proper amperage, and to provide a visible signal if desired. The wires 38 and 39 connect respectively with track wires 41 and 42, one leading to one track and one to the 10 other. The wire 41 is connected at one end to a binding post 43 on the insulator base 13 of the switch, in which binding post the wiring for the magnet 11 is connected. The other end of the wire 41 is connected to the 15 binding post 32 on the release. The wire 42 connects with its switch and release in the same manner. Wires 44 and 45, one for each circuit, are each connected at one end to a binding post 46 on the base 13, to which 20 binding post the wiring for the magnet 10 is connected. The other end of the wire 44 or 45 is connected to a binding post 47 carried on the contact 26 of the release.

30. The operation of the construction shown is as follows: The mechanism for both tracks is the same and the operations are alike. When a train approaches a crossing the rail 3 is depressed at the place where the ties 2 are cut away adjacent to the switch. The depression of the rail causes the end 8 of the switch bar to move downwardly, and the block 22 forces the magnet end of the lever 16 downwardly thereby bringing the contact 19 into engagement 35 with the contact 18 and establishing electrical connection from the track wire to the rail through the lever 16, posts 15 and wires 23 and causes the bell to ring. The 40 current energizes the magnet 10 which acts on the armature 17 and holds the lever end down until the current is broken by the release 6. As the train passes the crossing the rail adjacent to the release is depressed, and the bar 24 is forced downwardly, thereby 45 carrying the contact 29 out of engagement with the contact 26, and breaking the circuit. When the current is broken by the release the weight 21 on the lever 16 forces the contact 19 out of engagement with the 50 contact 18 and holds it in such position until the rail 3 at the switch is again depressed. When the circuit is made by the action of the switch the current passes through the tap 35, bell and lamps, to the track wire, 55 then dividing on the track wire, one portion goes to the binding post 43 and through magnet 11 and core 14 to contact 18. The other portion of the current goes to the binding post 32 on the release, through wire 60 33, contacts 29 and 26, binding post 47, wire

44 to binding post 46 on the switch, then through magnet 10 to contact 18. From contact 18 the united current passes through lever 16, posts 15 and wires 23 to rail 3. The magnet 11 equalizes the current passing through the wires of the switch magnet 10, and by affording a path of lower resistance than the air gap caused when the release is operated, prevents arcing at the release. 70

Obviously the device may be employed for signals on a single track system by making slight changes in the wiring, and it is also adaptable for many other purposes than for 75 crossing signals.

80 While I have shown but one specific embodiment of the invention, it will be understood that various details of the construction shown may be varied or omitted without departing from the spirit of this invention.

85 I claim.

1. An electrical signaling device, comprising a vertically movable track rail, a resilient bar rigidly supported at one end and having its other end projecting beneath the head of the rail, an operating magnet beneath said bar, an equalizing magnet beneath said bar and adapted to prevent arcing when the circuit is broken, said magnets being connected parallel in a circuit, a contact on the operating magnet, a lever pivotally supported beneath the bar, a contact on the lever adapted to engage the contact on the operating magnet, a counterweight on the lever adapted to normally keep the contacts separated, an armature on the lever adapted to be attracted by the operating magnet and hold the contacts in engagement and means on the bar adapted to force the lever downwardly. 95

100 2. An electrical signaling device, comprising a normally open circuit including a movable rail, means adapted to break the circuit at a second point, an operating magnet connected in the circuit, an equalizing magnet connected in the circuit parallel 110 with the operating magnet and adapted to prevent arcing when the circuit is broken, a resilient bar having one end rigidly supported and the other end projecting beneath the head of the movable rail, a pivotally supported lever having one end projecting above the operating magnet, an armature on the lever adapted to be attracted by said magnet, means on the bar adapted to move 115 the armature into engagement with the operating magnet when the rail is depressed and close the circuit at the normally open point, and conductors connecting said lever with the rail. 120

125 3. An electrical signaling device, comprising a magnet having a contact thereon, a pivotally supported lever having a contact adapted to coöperate with the contact on the magnet, an armature on the lever adapt- 130

ing the magnet to hold the lever in position for the contacts to engage each other, and a resilient bar rigidly supported at one end in position for its free end to operate said lever.

4. An electrical signaling device, comprising a magnet having a contact thereon, a lever pivotally supported adjacent to the magnet, a contact on the lever adapted to 10 coat with the contact on the magnet, an adjustable weight on the lever adapted to normally hold the lever contact away from the magnet contact, and a spring bar rigidly supported at one end adjacent to the magnet 15 and adapted to operate the lever with the other end.
5. An electrical signaling device, comprising a movable track rail, a magnet having a

contact thereon, a pivotally supported lever, means on the lever adapted to normally hold it out of operative position, a contact on the lever adapted to engage the contact on the magnet, and a spring bar rigidly supported at one end, and having its other end positioned to be operated by the depression 25 of the rail and to engage the lever and throw the lever contact into engagement with the magnet contact.

In witness whereof I have hereunto subscribed my name in the presence of two witnesses.

EDWARD A. FITZGERALD.
